(57) **CLAIM**

The ornamental design for a fire-proof storage box, as shown and described.

DESCRIPTION

FIG. 1 is a first perspective view of a fire-proof storage box showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of the fire-proof storage box in a closed configuration thereof;

FIG. 9 is a perspective view of the fire-proof storage box in a collapsed configuration thereof; and,

FIG. 10 is an enlarged view of the selected portion in FIG. 1.
